U.S. Appl. No. 29/301,729, filed Mar. 13, 2008 for Applicant for Mugge et al.

Primary Examiner — Anhdao Doan

(74) *Attorney, Agent, or Firm* — Merchant & Gould P.C.

(57) **CLAIM**

The ornamental design for a molded surface of a concrete product, as shown and described.

DESCRIPTION

FIG. 1 is a front view of a concrete product, according to our new design;

FIG. 2 is a right side view of the concrete product of FIG. 1; FIG. 3 is a left side view of the concrete product of FIG. 1; FIG. 4 is a top view of the concrete product of FIG. 1; FIG. 5 is a bottom view of the concrete product of FIG. 1; and, FIG. 6 is a perspective view of the concrete product of FIG. 1. The broken lines in the drawing views are included for the purpose of illustrating portions of the molded surface of a concrete product that form no part of the claimed design.

1 Claim, 6 Drawing Sheets
